US00D811746S

(12) **United States Design Patent** (10) **Patent No.:** **US D811,746 S**
Seiders et al. (45) **Date of Patent:** **** Mar. 6, 2018**

(54) **INSULATING DEVICE**(71) Applicant: **YETI Coolers, LLC**, Austin, TX (US)(72) Inventors: **Roy Joseph Seiders**, Austin, TX (US);
Christopher M. Keller, Austin, TX (US)(73) Assignee: **YETI Coolers, LLC**, Austin, TX (US)(***) Term: **15 Years**(21) Appl. No.: **29/544,625**(22) Filed: **Nov. 4, 2015****Related U.S. Application Data**

(63) Continuation of application No. 29/503,060, filed on Sep. 23, 2014.

CLAIM

The ornamental design for an insulating device, as shown and described.

DESCRIPTION

FIG. 1 is a top, front, left perspective view of an insulating device showing our new design;

FIG. 2 is a front view thereof;

FIG. 3 is a left side view thereof;

FIG. 4 is a right side view thereof; and,

FIG. 5 is a top view thereof.

The broken lines showing the remainder of the insulating device are for the purpose of depicting environmental subject matter which forms no part of the claimed design. The stipple shading in the drawings is a drawing convention and does not illustrate material, surface ornamentation, or surface decoration.
